UNITED STATES PATENT OFFICE.

WILLIAM LONGEWAY, OF GARY, INDIANA.

BREATHING APPLIANCE.

1,078,364.

Specification of Letters Patent.

Patented Nov. 11, 1913.

Application filed August 15, 1913. Serial No. 784,949.

To all whom it may concern:

Be it known that I, WILLIAM LONGEWAY, residing at Gary, in the county of Lake and State of Indiana, have invented a new and 5 Improved Breathing Appliance, of which the following is a specification.

This invention relates to that class of breathing appliances more especially designed for use in emergencies, particularly 10 by firemen; and it has for its purpose to provide an appliance of the general character stated of a simple and inexpensive character easily applied for use and efficient in operation.

15 Another object of my invention is the provision of an emergency breathing appliance that requires no special manipulation or assembling of parts, in its practical application, and in which the several parts 20 are so designed and coöperatively arranged so the entire outfit can be folded up into a package that may be readily carried in the pocket of the user, and in which the means for holding the parts to their folded or 25 compact shape can be quickly released for an emergency use of the appliance.

My invention also has for its object to provide an appliance of the character stated in which the vizor can be folded into the 30 tubing folds and secured against danger of breaking, and in which the means utilized for holding the appliance over the face of the user is also utilized for retaining the parts in their packed or folded up condition.

35 With the above objects in view, my invention consists in a breathing appliance that embodies the peculiar construction and coöperative arrangement of the parts hereinafter fully explained, specifically pointed 40 out in the appended claims, and illustrated in the accompanying drawings, in which:

Figure 1 is a perspective view of my invention, the same being shown as operatively applied for use. Fig. 2 is a side elevation of the upper end thereof. Fig. 3 is a detail cross section taken on the line 3—3 on Fig. 2. Fig. 4 is a front view of the upper or vizor portion of the appliance. Fig. 5 is a detail perspective view that illustrates the manner in which the supporting 45 rings are secured to the breathing tube. Fig. 6 is a detail perspective view that illustrates the manner of applying the supplemental fastener and protecting 50

tape hereinafter again referred to. Figs. 7 and 8 are detail cross sections taken on the 55 lines 7—7 and 8—8, on Figs. 5 and 6, respectively. Fig. 9 is a perspective view that illustrates the manner in which the vizor portion is folded into shape. Fig. 10 is a perspective view of my appliance 60 folded into its compact form to thereby adapt it for being carried in the pocket of the user.

In its practical arrangement, my improved breathing appliance comprises an 65 upper or vizor portion shaped to cover the face of the user and a pendent tube-like portion 10, the latter and the face portion being preferably of canvas or like material. The vizor portion 1 has a pair of glazed 70 sight openings 2 that are suitably formed in the said portion and arranged in any well known manner to thereby prevent moisture accumulating within the face covering and depositing on the inside of the glazed openings. To hold the vizor portion that covers 75 the face clamped against the head and under the chin of the user, the front or edge portion of the said covering has an elastic 4 held within the hem 5 of the said edge portion (see Fig. 3).

By reason of fitting the face covering tightly over the face, as stated and shown, outside air is prevented from entering the face covering around the edges thereof. 85

For securely holding the appliance on the head of the user, a wide elastic band 6 is provided, the ends of which are stitched to the opposite sides of the face covering adjacent the openings, as is clearly shown in 90 Figs. 2 and 4.

The depending air tube, which is gradually tapering toward the lower end, is provided at suitable intervals with annular stiffener or supporting rings 7—7, three of 95 such rings being shown, and these are of progressively reduced diameter, the smallest at the bottom. These rings at all times hold the tube open, when the appliance is in use, for the free passage of air to the user. The 100 several rings are each secured to the tube by a number of stitches 8, that are sewn through the outside of the tube across the top and bottom edges of the rings. To further hold the rings in place, and at the same time protect the stitches 8, an insulator tape covering 105

9, is wound around the rings, as is best shown in Fig. 6.

By reason of forming the several rings and making the tube tapered, as stated and shown, when not in use, the appliance can be folded up into such a small compass that it may be readily carried in the pocket of the user, since the lowermost ring with that portion of the tube between it and the next 10 ring can be telescopically moved into the next ring above and the said next ring and its tube portion above it likewise moved into the upper ring.

It will be seen that the rings may seat 15 within each other and are annularly corrugated, as shown.

The uppermost ring 8 is of such a diameter relatively to the vizor portion that in folding the said vizor portion down into the 20 upper ring, the two "eyes" or openings can be arranged flatwise, side by side, down within the said upper ring and thereby be held secure against breakage when carrying the appliance.

25 The face portion of the appliance is folded down over the upper ring and the several portions that constitute the complete appliance are held packed in a compact shape by the elastic head band which is held under 30 tension crosswise tightly over the package (see Fig. 10) by a half twist when snapping it over the said folded package.

From the foregoing description taken in connection with the drawing, the manner of 35 its use and the advantages of my invention will be readily understood by those skilled in the art to which it appertains. Among other advantages it should be mentioned, since it can be conveniently carried in the 40 pocket of the user, and the parts held together by the twisted elastic band, the user, a fireman,—for instance, in case of emergency, can quickly withdraw the package from his pocket and with the same hand 45 quickly unsnap the holding band and thereby have the appliance in shape for quickly fitting the same for use.

The function of corrugating the rings 7, as before mentioned, is to serve as a more 50 positive retainer of the ring in its place on the canvas tube, it being readily seen that when the tape 9 is wrapped around as in Fig. 6, the tape being pliable, will tend to conform to the undulations of the canvas 55 and ring beneath it, and so serve as a binder of the several thicknesses and also as an assistant to the stitches 8.

What I claim is:

1. A breathing appliance comprising a 60 flexible tapering tube-like body, the upper end of which is enlarged and shaped to fit over the face of the user and to form a vizor, means in the tube to hold it to an open position when in use, said means comprising 65 annular rings suitably spaced apart and of

progressively decreasing diameter and secured to the tube, said rings and the tubing portions between the rings being adapted for telescopically interengaging, and the upper ring being of a size to accommodate the 70 folding of the vizor portion down into and upon the upper one of the rings, and means for holding the parts to their folded condition.

2. A breathing appliance comprising a 75 flexible tapering tube-like body, the upper end of which is enlarged and shaped to fit over the face of the user and to form a vizor, means in the tube to hold it to an open position when in use, said means comprising annular rings suitably spaced apart and of 80 progressively decreasing diameter and secured to the tube, said rings and the tubing portions between the rings being adapted for telescopically interengaging, the upper ring being of a size to accommodate the folding of the vizor portion down into and upon the upper one of the rings, means for holding the parts to their folded condition, the said 85 means comprising a flexible band loop secured at its ends to the opposite edges of the vizor portion of the body, said band being adapted for being twisted across the said folded package, as set forth.

3. A breathing appliance comprising a 95 vizor having means for causing it to fit airtight over the face of the user, a flexible tapering air tube, rings of progressively decreasing diameter secured at intervals within the tube, the said rings and their intervening tube portions being adapted for telescopically folding within each other, stitching through the tube that passes over and under the rings, and insulating tapes wound around the tubing and the said stitching. 100

4. A breathing appliance comprising a 105 body formed of a flexible material and including a vizor having means for fitting it airtight over the face of the user, and a tapering air-tube pendent from the vizor, a 110 series of rings fitted at intervals on the inside of the tube, means for securing the rings to the tube, the said rings being of progressively decreasing diameters, the upper ring and the eye portions of the vizor being relatively such that the said eye portions of the 115 vizor can be folded side by side within the upper ring, the tube and the other rings being adapted for telescopically engaging each other and the upper ring and means secured to the vizor and comprising an elastic band for snapping over the tube, the rings and the vizor when the several parts are folded 120 together.

5. A breathing appliance comprising a 125 flexible tapering tube-like body, the upper end of which is enlarged and shaped to fit over the face of the user and to form a vizor, means in the tube to hold it to the open position when in use, the said means com- 130

prising annularly corrugated rings suitably spaced apart and of progressively decreasing diameter, means for securing the rings to the tube, said means including a pliable 5 tape wound around the canvas at a point over the corrugated rings, the said rings and the tube portions between the rings being adapted for telescopically interengaging with each other.

WILLIAM LONGEWAY.
